(57) **CLAIM**

The ornamental design for a can lid, as shown and described.

DESCRIPTION

FIG. 1 is a left side view of a can lid of the present invention; FIG. 2 is right side view of a can lid of the present invention; FIG. 3 is a front side view of a can lid of the present invention;

FIG. 4 is a rear side view of a can lid of the present invention;

FIG. 5 is a top planar view of a can lid of the present invention;

FIG. 6 is a bottom planar view of a can lid of the present invention;

FIG. 7 is a sectional view of a can lid of the present invention, wherein the can opening device is shown in the closed position.

FIG. 8 is a top front perspective view of a can lid of the present invention, wherein the can opening device is in the closed position;

FIG. 9 is a top front perspective view of the can lid disposed on a can of the present invention, wherein the can opening device is in the closed position;

FIG. 10 is a top front perspective view of the can lid disposed on a can of the present invention, wherein the can opening device is in the open position; and,

FIG. 11 is a top front perspective view of the can lid disposed on a can of the present invention, wherein the can opening device has returned to the closed position after opening of the can has occurred.

The broken line showing of a can in FIGS. 9, 10 and 11 is for illustrative purposes only and forms no part of the claimed design.
